UNITED STATES PATENT OFFICE.

CHARLES E. SKELTON, OF EAST ONONDAGA, NEW YORK.

LOOSE-LEAF BINDER.

1,316,198.

Specification of Letters Patent. Patented Sept. 16, 1919.

Application filed June 27, 1918. Serial No. 242,237.

To all whom it may concern:

Be it known that I, CHARLES E. SKELTON, a citizen of the United States, and a resident of East Onondaga, in the county of 5 Onondaga and State of New York, have invented a certain new and useful Loose-Leaf Binder, of which the following is a specification.

This invention relates to loose leaf binders and has for its object a particularly simple and efficient loose leaf binding means by which the covers and leaves are readily detached and attached without manipulation of fastening devices as screws, rods, etc., 10 and the invention consists in the novel features and in the combinations and constructions hereinafter set forth and claimed.

In describing this invention, reference is had to the accompanying drawings in which 20 like characters designate corresponding parts in all the views.

Figure 1 is an edge view of a loose leaf binder embodying my invention.

Fig. 2 is a detail view illustrating the 25 unlocking action of the cover, one of the covers being shown as folded into wide open position and as detached or about to be attached to the binding post.

Fig. 3 is a detail view illustrating in plan 30 the hinge members connecting the binding posts and covers.

Figs. 4 and 5 are enlarged detail views 35 of the hinge members, Fig. 4 being in plan, and the body or plate of the female member being broken away and Fig. 5 being an elevation.

This loose leaf binder comprises, generally, covers and leaf binding means, one of the covers and said means having normally 40 interlocked parts arranged to unlock upon folding back of the cover into open position, said means being arranged to lock and unlock upon an edgewise movement of the cover when in open position.

1 designates the covers which may be of 45 any suitable form, size and construction.

2 are the leaf binding members which are here shown as posts, each cover and the 50 posts having hinge members which are arranged to lock and unlock when the covers are swung into open position and upon edgewise movement of the cover.

As here shown, the covers are provided 55 with female hinge members 3 at their binding edges in the form of sockets open at one side here shown as the side toward the

free edge of the cover, the sockets having transverse slots 4 in their outer walls which open through the edges of the outer walls at the open sides of the sockets; and the 60 posts are provided with heads or balls 5 at their ends and necks 6 connecting the balls and the bodies of the post, the balls entering the sockets and the necks entering the slots upon edgewise movement of the 65 cover to the right, Fig. 2, when the cover is in open position, and being detachable upon the reverse of this movement.

The sockets are provided on plates 7 secured in any suitable manner to the inner 70 faces of the covers at the binding margins thereof and are located directly behind but spaced apart from the binding edges of the covers in order to permit the edgewise movement of the covers to engage and disengage the sockets 3 from the posts 2. The open sides of the sockets face the binding or rear edges of the covers. The covers are bound together by a flexible binding member 8 extending around the bound edges of 80 the leaves 9 and secured at its opposite margins to the outer faces of the covers so that the hinge members 4 and 5 at opposite ends of the posts are housed or concealed by the binding member 8.

In operation, to place leaves on the binding posts, one cover is swung into open position and moved edgewise forwardly as shown in Fig. 2 and then moved rearwardly to expose the ends of the posts. The leaves 90 can then be placed on or removed from the posts, it being understood that the leaves are provided with suitable perforations for receiving the posts. The cover is then moved into the position shown in Fig. 2 and 95 moved to the right to interlock the sockets on the balls.

This loose leaf binder is particularly advantageous in that it is readily operated to remove and replace leaves without manipulating locking devices, as screws, rods, etc.

What I claim is:

1. A loose leaf binder comprising covers, and leaf binding means, one of the covers and said means having normally interlocked parts arranged to unlock upon folding back of the cover into open position, substantially as and for the purpose described.

2. A loose leaf binder comprising covers, and leaf binding means, one of the covers and said means having hinged parts as-

- ciated respectively therewith and arranged to detach when said cover is swung to open position, substantially as and for the purpose specified.
5. 3. A loose leaf binder having covers, and leaf binding means, one of the covers and said means having detachable interlocked hinge members arranged to be detached and attached together by an edgewise movement when said cover is open, substantially as and for the purpose set forth.
4. A loose leaf binder comprising covers, and leaf binding means, one of the covers and said means having detachable normally interlocked hinge members arranged to be detached and attached together by an edgewise movement toward or from the free edges of the leaves when said cover is open, substantially as and for the purpose described.
5. A loose leaf binder comprising covers and a leaf binding member, one of the covers and the leaf binding member having detachable normally interlocked members comprising a male hinge member on one of said parts hinged together and a female hinge member on the other of said parts, the female member being open at one side and having a transverse slot in its outer wall opening through the free edge of said wall at the open side of the socket, substantially as and for the purpose specified.
6. A loose leaf binder comprising covers, and a leaf binding member, one of the covers and said member having detachable normally interlocked hinge members comprising a socket on one of said parts hinged together, a head on the other of said parts and a neck adjacent the head, the socket being open at one side and having a transverse slot in its outer wall opening through the free edge of said wall at the open side of the socket, the head being located in the socket, and the neck extending through the slot, substantially as and for the purpose set forth.
7. A loose leaf binder comprising covers, and a leaf binding member, one of the covers and the leaf binding member having detachable normally interlocked hinge members comprising a socket on one of said parts hinged together and a head on the other of said parts for entering the socket and a neck adjacent the head, the socket having its side toward the free edge of the cover open and being provided with a transverse slot in its outer wall opening through the edge of said wall at the open side of the socket for receiving the neck, substantially as and for the purpose described.
8. A loose leaf binder comprising covers and a leaf binding post connecting the covers, the post being formed with a ball at one end and a neck connecting the ball and the body of the post, one of the covers being formed with a socket open at one side for receiving the ball and having a transverse slot in the outer wall thereof opening through the edge of said wall at the open side, the slot receiving the neck, substantially as and for the purpose specified.
9. A loose leaf binder comprising covers, leaf binding means, the covers and said means having normally interlocked parts arranged to unlock upon folding back of the covers into open position and binding means connecting the covers and inclosing the leaf binding means, substantially as and for the purpose set forth.
10. A loose leaf binder comprising covers, a leaf binding member, the covers and the leaf binding member having detachable normally interlocked hinge members comprising a male member on one of said parts hinged together, and a female member on the other of said parts, each female member being open at one side and having a transverse slot in its outer wall opening through the free edge of said wall at the open side of the socket, and cover binding means inclosing the hinge members of the leaf binding means, substantially as and for the purpose described.
11. A loose leaf binder comprising covers and leaf binding members, the covers and said members having detachable normally interlocked hinge members located in the rear and spaced from the binding edges of the covers constructed to unlock and interlock upon edgewise movement of the covers when in open position, the space between said hinge members and the binding edges of the covers permitting the edgewise unlocking movement, and means binding the covers together and inclosing said hinge members, substantially as and for the purpose specified.
12. A loose leaf binder comprising covers, binding posts, each post having balls at its opposite ends, and necks adjacent the balls, and the covers having sockets for receiving the balls, each socket being open at one side of and having a transverse slot in its outer wall opening through the free edge of the wall at the open side of the socket, the balls being located in the sockets and the necks extending through the slots, substantially as and for the purpose set forth.

In testimony whereof, I have hereunto signed my name, at Syracuse, in the county of Onondaga, and State of New York, this 25th day of May, 1918.

CHARLES E. SKELTON.
